UNITED STATES PATENT OFFICE.

GEORGE P. WIGGINTON, OF KALAMAZOO, MICHIGAN, ASSIGNOR TO THE KALAMAZOO LOOSE LEAF BINDER CO., OF KALAMAZOO, MICHIGAN.

TEMPORARY BINDER.

Application filed September 10, 1921. Serial No. 499,637.

To all whom it may concern:

Be it known that I, GEORGE P. WIGGINTON, a citizen of the United States, residing at the city and county of Kalamazoo, State 5 of Michigan, have invented certain new and useful Improvements in Temporary Binders, of which the following is a specification.

This invention relates to improvements in temporary binders.

10 The main objects of this invention are:

First, to provide an improved temporary binder or loose sheet holder well adapted for the holding of loose sheets, circulars and the like, which is easily adjusted to secure 15 the sheets and to permit their removal and insertion and at the same time one in which the sheets are securely held.

Second, to provide an improved binder for 20 loose sheets which is very simple and economical in structure and at the same time neat and attractive in appearance.

Further objects, and objects relating to 25 structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this application, in which:

Fig. I is a perspective view of a binder embodying the features of my invention.

35 Fig. II is a transverse section on a line corresponding to line 2—2 of Figs. I and III, parts being shown in full lines for convenience in illustration, the disengaged position of one of the coupling members being indicated by dotted lines.

40 Fig. III is a detail longitudinal section on a line corresponding to line 3—3 of Figs. I and II, parts being shown in full lines for convenience in illustration.

45 Fig. IV is a perspective view of one of the binding bars removed from its attaching flap.

Fig. V is a perspective view of one of the 50 sheet-engaging posts.

In the drawing similar reference characters refer to similar parts throughout the several views.

55 Referring to the drawing, the covers 1, 1 are, in the embodiment illustrated, connected

by a flexible back 2. Within the covers are binding bars 3, the same being hingedly secured by means of the binding flaps 4. These binding bars have inwardly projecting post-engaging studs 5, the studs of the two 60 bars being disposed out of alignment.

The sheet-engaging posts 6 are adapted to receive these studs, being preferably tubular, as illustrated, the bores providing sockets 7 for the studs.

65 The posts are provided with sheet-engaging heads 8. The sheets 9 are provided with aligned holes 10 adapted to receive the posts which are arranged therein from opposite sides so as to overlap in the sheet body, thus 70 binding the sheets together as a unit.

The sheet body is secured as a unit by inserting the posts and engaging the studs with the posts. The binding bars are adjustably connected by coupling members 11 75 formed of screw-connected sections 12 and 13, the section 12 being pivoted at 14 to the lower binding bar and the section 13 being provided with a head 15 detachably engageable with the slot 16 in the upper binding bar.

70 The coupling members may be readily adjusted according to the thickness of the sheet body.

85 My improved binder is attractive in appearance; there are no exposed metal parts and it may be easily manipulated for the insertion and removal of sheets; further, the sheets are very securely bound.

Having thus described my invention, what 90 I claim as new and desire to secure by Letters Patent, is:

1. In a temporary binder, the combination 95 with sheets provided with holes adapted to receive posts, of covers connected by a flexible back, binding bars hinged within said covers and having inwardly projecting studs aligned with the holes of said sheets, tubular posts engaging said holes in said sheets and provided with sheet-engaging heads, the 100 posts being arranged from both sides of the sheet body and overlapping therein, said studs being adapted to engage said posts whereby they are retained within the binder, and disengageable and extensible coupling 105 members for said binding bars disposed at the ends thereof.

2. In a temporary binder, the combination 110 with sheets provided with holes adapted to receive posts, of covers connected by a flexi-

ble back, binding bars hinged within said covers and having inwardly projecting studs aligned with the holes of said sheets, tubular posts engaging said holes in said sheets 5 and provided with sheet-engaging heads, the posts being arranged from both sides of the sheet body and overlapping therein, said studs being adapted to engage said posts whereby they are retained within the binder, 10 and coupling members for said binding bars.

3. In a temporary binder, the combination with sheets provided with holes adapted to receive posts, of binding bars having inwardly projecting studs aligned with the 15 holes of said sheets, tubular posts engaging said holes in said sheets and provided with sheet-engaging heads, the posts being arranged from both sides of the sheet body and overlapping therein, said studs being 20 adapted to engage said posts whereby they are retained within the binder, and disengageable and extensible coupling members for said binding bars disposed at the ends thereof.

25 4. In a temporary binder, the combination with sheets provided with holes adapted to receive posts, of binding bars having inwardly projecting studs aligned with the holes of said sheets, tubular posts engaging 30 said holes in said sheets and provided with sheet-engaging heads, the posts being arranged from both sides of the sheet body and overlapping therein, said studs being adapted to engage said posts whereby they are 35 retained within the binder, and coupling members for said binding bars.

5. In a temporary binder, the combination of the covers connected by a flexible back, binding bars hinged within said covers and 40 having inwardly projecting studs, the studs of one bar being out of alignment with

those of the other, sheet-engaging posts removably engaged with said studs and provided with sheet-engaging heads, and disengageable and extensible coupling members 45 for said binding bars disposed at the ends thereof.

6. In a temporary binder, the combination of the covers, binding bars having inwardly projecting studs, the studs of one bar being 50 out of alignment with those of the other, sheet-engaging posts removably engaged with said studs and provided with sheet-engaging heads, and disengageable and extensible coupling members 55 for said binding bars disposed at the ends thereof.

7. In a temporary binder, the combination of the covers connected by a flexible back, binding bars hinged within said covers and having inwardly projecting studs, the studs 60 of one bar being out of alignment with those of the other, sheet-engaging posts removably engaged with said studs and provided with sheet-engaging heads, and coupling members 65 for said binding bars disposed at the ends thereof.

8. In a temporary binder, the combination of the covers, binding bars having inwardly projecting studs, the studs of one bar being out of alignment with those of the other, sheet-engaging posts removably engaged 70 with said studs and provided with sheet-engaging heads, and coupling members for said binding bars disposed at the ends thereof.

In witness whereof, I have hereunto set my hand and seal in the presence of two witnesses.

GEORGE P. WIGGINTON. [l. s.]
